UNITED STATES PATENT OFFICE

LEON T. MART, OF KANSAS CITY, MISSOURI

STEAM SEPARATOR

Application filed May 23, 1925. Serial No. 32,521.

The purpose of my invention is to provide a steam separator capable of insertion within a pipe or upon the exterior of any steam generator or holder.

- 5 A purpose of my invention is to provide an advantageous arrangement and combination of parts to form a separator unit just outside of the boiler, draining back through the steam outlet into the boiler.
- 10 A further purpose is to provide for distribution of the steam outwardly and downwardly about an interior chamber to spread it centrifugally within the chamber, and to drain the water separated from within the chamber.

15 A further purpose is to free from water entrainment upon an outlet wall by centrifugal withdrawal of the water close to the wall.

- 20 A further purpose is to pass the steam from a boiler outlet up around the sides of an internal bowl, to discharge downwardly and tangentially into the top of the bowl at high circumferential velocity throwing the water 25 out upon the bowl interior, to drain the water through a suitable drain pipe, to pass the dry steam upwardly from the central portion of the bowl into the steam line.

30 Further purposes will appear in the specification and in the claims.

In the drawings I have preferred to illustrate only one main form of my invention, with modifications and have selected a form that is convenient and inexpensive to manufacture, efficient in operation, and which illustrates particularly well the principles involved.

35 Figure 1 is an elevation and illustrates my invention applied to a horizontal boiler.

40 Figure 2 is an enlarged section of the separator.

Figure 3 is a section taken upon the line 3—3 of Figure 2.

45 Figures 4, 5 and 6 are fragmentary perspectives showing steam passages.

Figures 7 and 8 and Figure 9 are views illustrating minor modifications, and correspond to enlarged fragments of Figures 1 and 2 respectively.

Like numerals refer to like parts in all figures.

Describing in illustration and not in limitation and referring to the drawings:

I show conventionally a boiler 10 having a steam outlet 11, with my separator unit 12 inserted between the outlet and the dry steam line 13, illustrating one of the locations to which my separator is adapted. Upper and lower flanges 14 and 15 of the separator unit mate with flanges 16 and 17 of the steam line and boiler outlet respectively. The needed heat insulation has been omitted for clearness of illustration.

The separator is conveniently divided into three or four parts to facilitate manufacture and as shown comprises an outer case 18 flanged at 15, cover 19 flanged at 14, an inner bowl 20 and a spacing and steam-directing ring 21.

The outer casing is flanged at 22 for union with the cap by any suitable fastenings.

The ring 21 spaces the inner bowl 20 from a skirt or shell 23 depending from the cap so as to provide an annular passage 24 between the upper part of the bowl and the skirt. The ring is fluted diagonally or spirally presenting passages 24' between ribs 26 so as to give centrifugal motion to the steam as it passes through these passages. The passages may incline also to turn the steam toward the inner surface of the bowl and may discharge in the outer portion of the passage 24 near to this inner bowl surface, increasing the effect.

For convenience the bowl is supported from the skirt through the ring and any suitable fastenings such as pins 27. The passage 24 is formed between the cylindrical wall of the bowl and the lower end of the skirt or

shell 23 extended some distance below the flutings as at 28.

The water collecting within the bowl is drained by pipe 29 into the boiler where the end of the pipe is check-valved at 30.

5 Three forms of flutings are shown in Figures 4, 5 and 6 to show the fact that the end to be accomplished can be secured in a variety of ways, without attempting to illustrate all 10 of the ways or all of the combinations of those shown which may be used.

15 Here the rings 21¹, 21² and 21³ are all of them so fluted or apertured—here viewed as effectively the same thing—as to discharge from that portion of the lower face 31 of each 20 ring which is of larger diameter so as to discharge closer to the interior cylindrical wall of the bowl than to the exterior cylindrical wall of the skirt 23.

25 In each of the forms shown in Figures 4 and 5 the flutings are tapered, being larger at the inlet opening than at the outlet opening for the purpose of increasing the velocity of the steam as it passes through the flutings. This is accomplished in the case of the flutting or passage 24¹ by giving it greater width at the inlet opening than at the outlet. In the passage 24² (Figure 5) the same purpose is accomplished by giving the passage greater 30 depth at the inlet than at the outlet. This secures an additional advantage of giving diagonal outward flow to a portion of the steam which passes through.

35 In each of these Figures 4 and 5 the flutting is not only diagonal to the elemental lines of the adjoining cylindrical surfaces but is desirably spiralled. In Figure 6, however, the flutting or passage 24³ is not tapered and is not spiralled but is diagonal with respect to the elemental lines of the cylindrical surfaces and slopes also toward the axis of these cylinders 40 thus giving centrifugal movement and also outward flow to the entire body of the steam.

45 In operation the steam passes up through the space 32 along the outer side 33 of the bowl, then downwardly through the flutings and the passage 24 and upwardly through the shell to the steam outlet. The centrifugal action of the steam and any outward direction of flow given it in passing downwardly through the flutings is depended upon to throw the water in the steam outwardly against the interior 34 of the bowl so as to avoid danger of entrainment of water in the 50 steam passing out into the supply pipe. This principle is present throughout my illustrations.

55 However, in Figures 7 and 8 I show further provision for avoiding entrainment of the water in two different ways. I place a ribbed member 35 (Figure 7) in the bottom of the inner chamber so that the steam will impinge against the crow's-foot as it turns to pass out of the drum.

60 85 In Figure 8 I show the lower edge of the

skirt or shell as shrouded or flanged inwardly and upwardly at 36 so that any water which may tend to follow the surface 37 of the skirt or shell downwardly and turn along the inner edge of the skirt will follow the lower and inner surface 38 of this shroud or flange and will turn about its upper edge 39 so as to flow within the annular space 40 between the shroud and the skirt. From this space 40 it may be drained to the 75 lower part of the separation chamber within the bowl by means of a pipe 41.

70 In view of my invention and disclosure variations and modifications to meet individual whim or particular need will doubtless become evident to others skilled in the art and I therefore claim all such in so far as they fall within the reasonable spirit and scope of my invention.

75 Having thus described my invention, what I claim as new and desire to secure by Letters Patent is:—

1. A steam separator, comprising an outer casing having an inlet at the lower end, an inner cylindrical bowl therein, walls forming an outlet from the bowl, a water drain from the bowl and walls forming passages within the bowl and said outlet forming walls whose inlets are nearer the axis of the 80 bowl than their outlets.

90 2. A steam separator comprising an outer casing having an opening at its lower end, a bowl within the outer casing having spiralled openings about its upper end to admit steam from the casing to the interior of the bowl, a centrally apertured closure for the casing and bowl extending in cylindrical form into the bowl to a point below the spiralled openings, flanges within the bottom of the bowl upon which the steam impinges, a shroud within the extension of the closure 95 and means for water drainage into the bowl from the space above the shroud.

100 3. A steam separator, comprising an outer casing having an opening at its lower end, a bowl within the outer casing having spiralled openings about its upper end admitting steam from the casing to the interior of the bowl, a closure for the casing and bowl extending cylindrically into the bowl to a point below the spiralled openings, the outlets of the openings being nearer radially to the interior wall of the bowl than to the extension.

110 4. A steam separator, comprising an outer casing having an opening at its lower end, a bowl within the outer casing having tapered spiralled openings about its upper end admitting steam from the casing to the interior of the bowl, a closure for the casing and bowl extending cylindrically into the bowl to a point below the spiralled openings, the outlets of the openings being nearer radially to the interior wall of the bowl than to the extension.

5. In a steam separator, an outer casing open at the lower end, a bowl therein having its open end toward the outer end of the casing, an apertured cover closing the ends of the bowl and casing except for the aperture which forms an outlet from the bowl, a depending skirt hanging down from the cover into the bowl and walls providing spiralled passage for steam within the bowl and said depending skirt radially nearer to the inner surface of the bowl than to the outer surface of the skirt.
